(57) **ABSTRACT**

A heating wire of an electronic atomizing device includes a central end, a distal end, and a plurality of spiral heating coils extending between the central end and the distal end. The plurality of spiral heating coils is coplanar and surrounds the central end. A mounting gap is formed between any two adjacent spiral heating coils in an extending direction of a reference line connecting the center end and the distal end. The widths of the mounting gaps gradually decrease along the extending direction of the reference line away from the central end. An electronic atomizing device including the aforementioned heating wire is further provided.

HEATING WIRE AND ELECTRONIC
ATOMIZING DEVICE HAVING THE SAMECROSS-REFERENCE TO RELATED
APPLICATION

This application claims priority to Chinese Patent Application No. 201910063034.8, entitled "HEATING WIRE AND ELECTRONIC ATOMIZING DEVICE HAVING THE SAME" filed Jan. 23, 2019, the contents of which are expressly incorporated by reference herein in its entirety.

TECHNICAL FIELD

The present disclosure relates to electronic atomizing devices.

BACKGROUND

For an electronic atomizing device which heats solid tobacco paste to be atomized, a heating wire is generally used to heat a bowl in which the tobacco paste is stored. However, since the bowl of the conventional electronic atomizing device is heated unevenly and thus has an unevenly distributed temperature field at the bottom thereof, uneven heating of the tobacco paste is resulted, such that bubbles are easily generated from the tobacco paste, and explosion of the bubbles may cause the tobacco paste splash. Meanwhile, user's suction experience of the electronic atomizing device is ultimately affected as a part of the tobacco paste subjected to a high temperature is scorched and carbonized and the other part of the tobacco paste subjected to a low temperature is burned inadequately.

SUMMARY

According to various embodiments, a heating wire and an electronic atomizing device are provided.

A heating wire of an electronic atomizing device is providing, the heating wire including: a central end; a distal end; and a plurality of spiral heating coils extending between the central end and the distal end, the plurality of spiral heating coils being coplanar and surrounding the central end, wherein a mounting gap is formed between any two adjacent spiral heating coils in an extending direction of a reference line connecting the center end and the distal end, and the widths of the mounting gaps gradually decrease along the extending direction of the reference line away from the central end.

An electronic atomizing device is provided, including a heating wire, wherein the heating wire includes: a central end; a distal end; and a plurality of spiral heating coils extending between the central end and the distal end, the plurality of spiral heating coils being coplanar and surrounding the central end, wherein a mounting gap is formed between any two adjacent spiral heating coils in an extending direction of a reference line connecting the center end and the distal end, and the widths of the mounting gaps gradually decrease along the extending direction of the reference line away from the central end.

These and other objects, advantages, purposes and features will become apparent upon review of the following specification in conjunction with the drawings.

BRIEF DESCRIPTION OF THE DRAWINGS

To illustrate the technical solutions according to the embodiments of the present invention or in the prior art more

2

clearly, the accompanying drawings for describing the embodiments or the prior art are introduced briefly in the following. Apparently, the accompanying drawings in the following description are only some embodiments of the present invention, and persons of ordinary skill in the art can derive other drawings from the accompanying drawings without creative efforts.

FIG. 1 is a plan view of a heating wire according to an embodiment.

FIG. 2 is a perspective view of a heating wire of FIG. 1.

FIG. 3 is a plan view of a heating wire according to another embodiment.

FIG. 4 is an exploded view of an electronic atomizing device according to an embodiment.

FIG. 5 is a perspective view of a bowl and an insulating sheet of FIG. 4.

FIG. 6 is a cross-sectional view taken along line A-A of FIG. 5.

DETAILED DESCRIPTION OF THE
EMBODIMENTS

Embodiments of the invention are described more fully hereinafter with reference to the accompanying drawings. The various embodiments of the invention may, however, be embodied in many different forms and should not be construed as limited to the embodiments set forth herein. Rather, these embodiments are provided so that this disclosure will be thorough and complete, and will fully convey the scope of the invention to those skilled in the art. Elements that are identified using the same or similar reference characters refer to the same or similar elements.

It will be understood that when an element is referred to as being "connected" or "coupled" to another element, it can be directly connected or coupled to the other element or intervening elements may be present. In contrast, if an element is referred to as being "directly connected" or "directly coupled" to another element, there are no intervening elements present.

It will be understood that, although the terms first, second, etc. may be used herein to describe various elements, these elements should not be limited by these terms. These terms are only used to distinguish one element from another. Thus, a first element could be termed a second element without departing from the teachings of the present invention.

Referring to FIG. 1, FIG. 4, and FIG. 6, a heating wire 10 of an electronic atomizing device 20 is provided according to an embodiment. The heating wire 10 is used to heat a solid tobacco paste in a bowl 200. The heating wire 10 includes a central end 11, a distal end 13, and a plurality of spiral heating coils 110 extending between the central end 11 and the distal end 13. The plurality of spiral heating coils 110 are coplanar and surround the central end 11. The spiral heating coil 110 is shaped as a curve on a plane that winds around a fixed center point (e.g. the central end 11) at a continuously increasing distance from the point. Assuming there is a reference line 12 starting from the center end 11 and extending towards the distal end 13, then the reference line 12 intersects with each of the spiral heating coils 110 at 50 multiply points. In the illustrated embodiment, at least three mounting gaps 120 are provided between any two adjacent spiral heating coils 110 in an extending direction of the reference line 12. The widths of the mounting gaps 120 gradually decrease along the extending direction of the reference line 12 away from the central end 11. In other words, the mounting gap 120 between two adjacent spiral heating coils 110 located further from the central end 11 has a width

smaller than that of the mounting gap 120 between two adjacent spiral heating coils 110 located closer to the central end 11.

Referring to FIG. 1, in the illustrated embodiment, the heating wire 10 has four spiral heating coils 110, i.e., a first heating coil 111, a second heating coil 112, a third heating coil 113, and a fourth heating coil 114, which are sequentially arranged from the inside out. The central end 11 is located at a center of the first heating coil 111. The reference line 12 starts from the central end 11 and intersects with the first heating coil 111 at point A, intersects with the second heating coil 112 at points B and C, intersects with the third heating coil 113 at points D and E, and intersects with the fourth heating coil 114 at point F in sequence.

A first mounting gap 121 is formed between the first heating coil 111 and the second heating coil 112 in the extending direction of the reference line 12 and has a width of D_1 , which is the distance between the point A and the point B. A second mounting gap 122 is formed between the second heating coil 112 and the third heating coil 113 in the extending direction of the reference line 12 and has a width of D_2 , which is the distance between the point C and the point D. A third mounting gap 123 is formed between the third heating coil 113 and the fourth heating coil 114 in the extending direction of the reference line 12 and has a width of D_3 , which is the distance between the point E and the point F.

The heating coils of the conventional heating wire are arranged at equal intervals, in other words, intervals between two adjacent heating coils are constant from the central to the periphery of the heating wire. Since the heat generated by per unit length of the heating wire 10 is equal, temperature generated by such conventional heating wire might unevenly distributed as the periphery of the tobacco paste has a larger bulk than that of the central thereof and thus requires more heat to be atomized. By configuring the spiral heating coils 110 according to the aforementioned manner, the spiral heating coils 110 are densely arranged in the periphery, such that the temperature field generated by the spiral heating coils 110 is evenly distributed from the center to the periphery of the heating wire 10 comparing with the prior art. The bowl 200 is heated evenly by the heating wire 10, such that it can prevent the tobacco paste in the bowl 200 from splashing or explosion. In addition, it can avoid that scorched flavor is generated as the tobacco paste is scorched due to an over-heated temperature, and that concentration of the smoke generated from the atomized tobacco paste is lowered as the tobacco paste is burned inadequately due to a low temperature, such that the user's taste and suction experience is improved.

In some embodiments, when a diameter of the bowl 200 ranges from about 10 mm to about 18 mm, D_1 is equal to 1.3 to 1.8 times of D_2 , and D_1 is equal to 3.5 to 4 times of D_3 . In an embodiment, when the bowl 200 has a diameter of about 16 mm, $D_1=1.5D_2=3.8D_3$. In that case, the temperature field generated by the heating wire 10 is evenly distributed, such that the tobacco paste is heated evenly with a good atomization effect, and the energy waste of the heating wire 10 due to the locally high temperature is prevented, and a higher energy efficiency of the heating wire 10 is ensured.

Referring to FIG. 3, in the illustrated embodiment, the heating wire 10 has five spiral heating coils 110, i.e., a first heating coil 111, a second heating coil 112, a third heating coil 113, a fourth heating coil 114, and a fifth heating coil 115, which are sequentially arranged from the inside out. Similar to the embodiment illustrated in FIG. 1, the reference line 12 starts from the central end 11 and first intersects

with the first heating coil 111 at point A, intersects with the second heating coil 112 at points B and C, intersects with the third heating coil 113 at points D and E, intersects with the fourth heating coil 114 at points F and G, and intersects with the fifth heating coil 115 at point H in sequence.

A first mounting gap 121 is formed between the first heating coil 111 and the second heating coil 112 in the extending direction of the reference line 12 and has a width of D_1 , which is the distance between the point A and the point B. A second mounting gap 122 is formed between the second heating coil 112 and the third heating coil 113 in the extending direction of the reference line 12 and has a width of D_2 , which is the distance between the point C and the point D. A third mounting gap 123 is formed between the third heating coil 113 and the fourth heating coil 114 in the extending direction of the reference line 12 and has a width of D_3 , which is the distance between the point E and the point F. A forth mounting gap 124 is formed between the fourth heating coil 114 and the fifth heating coil 115 in the extending direction of the reference line 12 and has a width of D_4 , which is the distance between the point G and the point H.

In some embodiments, when a diameter of the bowl 200 ranges from about 18 mm to about 25 mm, D_1 is equal to 1.2 to 1.5 times of D_2 , and D_1 is equal to 2.2 to 3 times of D_3 , and D_1 is equal to 4 to 6 times of D_4 . In an embodiment, when the bowl 200 has a diameter of about 22 mm, $D_1=1.3D_2=2.5D_3=5D_4$. In that case, the temperature field generated by the heating wire 10 is evenly distributed, such that the tobacco paste is heated evenly with a good atomization effect, and the energy waste of the heating wire 10 due to the locally high temperature is prevented, and a higher energy efficiency of the heating wire 10 is ensured.

In some embodiments, the heating wire 10 is made of iron-chromium alloy or chromium-nickel alloy. The heating wire 10 made of such material has a better thermal conductivity and a higher melting point, and the heating speed to the bowl 200 and the tobacco paste and the service life of the whole heating wire 10 are improved.

Referring to FIG. 2, the heating wire 10 further includes a first leading wire 130 and a second leading wire 140 configured to be coupled to a positive and a negative electrodes (not shown), respectively. The first leading wire 130 is connected to the central end 11, and the second leading wire 140 is connected to the distal end 13. The first leading wire 130 and the second leading wire 140 are both located at the same side of a plane where the spiral heating coils 110 are located. In other embodiments, the first leading wire 130 and the second leading wire 140 may be located at opposite sides of the plane, respectively.

In some embodiments, the heating wire 10 has a length corresponding to the size of the bowl 200. For example, the length of the heating wire 10 can be about 70 mm, about 90 mm, about 150 mm or about 180 mm. The length of the heating wire 10 merely refers to a sum of the lengths of the whole spiral heating coils 110, and does not include the lengths of the first leading wire 130 and the second leading wire 140.

In some embodiments, a resistance of the heating wire 10 ranges from about 0.2Ω to about 2Ω , and each of the spiral heating coils 110 has a cross-section with a diameter which ranges from about 0.25 mm to about 0.8 mm.

Referring to FIGS. 4 to 6, an electronic atomizing device 20 is provided according to an embodiment, which includes the heating wire 10 according to any one of the aforementioned embodiments.

The electronic atomizing device **20** further includes the bowl **200** coaxially disposed with the heating wire **10**. The bowl **200** has a diameter larger than or equal to the diameter of the heating wire **10**, which ensures that the heat generated by the heating wire **10** is adequately transferred to the tobacco paste through the bowl **200**, such that the energy efficiency of the heating wire **10** is improved. In some embodiments, a diameter of the bowl **200** ranges from about 10 mm to about 25 mm. For example, the diameter of the bowl **200** may be about 10 mm, about 16 mm, about 22 mm ¹⁰ or about 25 mm.

The electronic atomizing device **20** further includes a heat insulating sheet **400** and an electric insulating sheet **300**. The heat insulating sheet **400** may be made of mica. The electric insulating sheet **300** may be made of ceramic. The heat insulating sheet **400** and the electric insulating sheet **300** are disposed opposite to each other, and the spiral heating coils **110** are sandwiched between the heat insulating sheet **400** and the electric insulating sheet **300**. The first leading wire **130** and the second leading wire **140** of the heating wire **10** ¹⁵ may extend through the heat insulating sheet **400** to be coupled to the electrodes. The bowl **200** is in contact with the electric insulating sheet **300**.

Since the electronic atomizing device **20** includes the aforementioned heating wire **10**, a good atomizing effect is ²⁰ resulted from the tobacco paste heated evenly, which improves the user's taste and suction experience of the electronic atomizing device **20**.

The foregoing respective technical features involved in the respective embodiments can be combined arbitrarily, for brevity, not all possible combinations of the respective technical features in the foregoing embodiments are described, however, to the extent they have no collision with each other, the combination of the respective technical features shall be considered to be within the scope of the ³⁰ description.

The foregoing implementations are merely specific the embodiment of the present disclosure, and are not intended to limit the protection scope of the present disclosure. It should be noted that any variation or replacement readily figured out by persons skilled in the art within the technical scope disclosed in the present disclosure shall all fall into the protection scope of the present disclosure. Therefore, the protection scope of the present disclosure shall be subject to the protection scope of the claims. ⁴⁰

What is claimed is:

1. An electronic atomizing device, comprising:
a heating wire, wherein the heating wire comprises:
a central end;

a distal end; and
a plurality of spiral heating coils extending between the central end and the distal end, the plurality of spiral heating coils being coplanar and surrounding the central end, wherein a mounting gap is formed between any two adjacent spiral heating coils of the plurality of spiral heating coils in an extending direction of a reference line connecting the center end and the distal end, and widths of the mounting gaps gradually decrease along the extending direction of the reference line away from the central end; ⁵

a bowl coaxially disposed with the heating wire, wherein a diameter the heating wire is less than or equal to a diameter of the bowl; and

a heat insulating sheet and an electric insulating sheet opposite to each other, wherein the plurality of spiral heating coils are sandwiched between the heat insulating sheet and the electric insulating sheet, and the bowl is in contact with the electric insulating sheet;

wherein the plurality of spiral heating coils comprises a first heating coil, a second heating coil, a third heating coil and a fourth heating coil sequentially arranged from the inside out, a first mounting gap formed between the first heating coil and the second heating coil in the extending direction of the reference line has a width of D_1 , a second mounting gap formed between the second heating coil and the third heating coil in the extending direction of the reference line has a width of D_2 , a third mounting gap formed between the third heating coil and the forth heating coil in the extending direction of the reference line has a width of D_3 , the bowl has a diameter of about 10 mm to about 18 mm, D_1 is equal to 1.3 to 1.8 times of D_2 , and D_1 is equal to 3.5 to 4 times of D_3 .

2. The electronic atomizing device of claim 1, wherein the heating wire further comprises a first leading wire and a second leading wire configured to be coupled to electrodes, respectively, the first leading wire is connected to the central end, and the second leading wire is connected to the distal end.

3. The electronic atomizing device of claim 2, wherein the first leading wire and the second leading wire are both located at the same side of a plane where the spiral heating coils are located.

4. The electronic atomizing device of claim 1, wherein the heating wire is made of iron-chromium alloy or chromium-nickel alloy.
